UNITED STATES PATENT OFFICE.

WILLIAM G. BENNETT, OF ADRIAN, WASHINGTON.

SPARK-INTENSIFIER FOR GASOLENE-ENGINES.

1,368,686.

Specification of Letters Patent.

Patented Feb. 15, 1921.

Application filed June 12, 1920. Serial No. 388,472.

To all whom it may concern:

Be it known that I, WILLIAM G. BENNETT, a citizen of the United States, residing at Adrian, in the county of Grant and State 5 of Washington, have invented certain new and useful Improvements in Spark-Intensifiers for Gasolene-Engines, of which the following is a specification, reference being had to the accompanying drawings.

10 This invention relates to improvements in spark intensifiers for gasolene engines.

An important object of the invention is to provide a device of the above character extremely simple in construction and which 15 may be readily and cheaply manufactured.

A further object of the invention is to provide a device of this character which is practically proof against short circuits.

Other objects of the invention will be 20 come apparent throughout the course of the following description.

In the accompanying drawings, wherein for the purpose of illustration is shown a preferred embodiment of my invention and 25 wherein like reference characters designate like parts throughout:

Figure 1 is a side elevation of my device, and

Fig. 2 is a transverse section taken there- 30 through.

Referring now more particularly to the drawings, the numeral 10 indicates a suitable body portion preferably formed of a single piece of insulating material such as 35 hard fiber, bakelite, hard rubber, or some similar material. The body portion is rectangular in form and is provided in the upper and lower edges thereof with spaced alined bores 11, which are interiorly thread- 40 ed and arranged in vertically opposed pairs. Transverse bores are formed in the side face of the body portion 10 to correspond in number and arrangement to the pairs of alined bores 11.

45 Similarly alined threaded bores 13 connect the corresponding bores 11 and 12, the bores 13 being adapted to receive adjustable electrodes generally taking the form of a brass screw or the like.

50 Sleeves 15 are provided preferably formed of the same material as the body portion 10 and having arranged within the bores thereof the ends of insulating wires 17 and conducting element 18 of the wire 55 projecting beyond the lower end of the sleeve. Washers 19 are provided having

central apertures adapted to receive the conducting element 18 and being of a diameter greater than the diameter of the bores 16 of the sleeves 15, and of less diameter than the 60 outside diameter of said sleeves. The conducting element as hereinbefore stated extends through the center apertures of the washers 19 and is folded back about the face of the washer. In my construction I pref- 65 erably employ a multiple wire conductor and the ends of this conductor are secured by mushrooming them back upon the washers. The lower end of the sleeve 15 is provided with external threads as at 21 adapt- 70 ed to coact with the threads of the aperture 11 in which the sleeve will be inserted. It will be seen that it is practically impossible to form a short circuit around and about the sleeve 15 in the conducting element and 75 screw 14 as the entire body portion and sleeve are formed of insulating material.

The transverse bores 12 are counterbored as at 22 for a short distance to form a shoulder 23. A sheet of mica or other similar 80 transparent insulating material rests against the shoulder and is retained in position by a spring retaining ring 24. It will be obvious to those familiar with the art 85 that the apparatus described in the preceding paragraphs is extremely simple and will have a small first cost and is not liable to get out of order.

Many changes being possible in the shape, size and arrangement of the various parts 90 shown, I do not limit myself to the particular arrangement hereinbefore set forth, but may make any such changes without departing from the spirit of the invention, or the scope of the subjoined claims. 95

Having now described my invention, what I claim is:

1. A device of the type described comprising, a body portion formed of insulating material and provided in opposed edges 100 with spaced threaded bores arranged in pairs, and transverse bores formed in the side face thereof corresponding in number and arrangement to the pairs of bores and extending intermediate the inner ends thereof, threaded bores formed in said body portion connecting each bore of each of said pairs with its corresponding transverse bore, externally threaded electrodes adjustable within said last named bores, sleeves formed 105 of insulating material and having one end thereof provided with external threads to

engage the threads of said first named bores, washers disposed within said bores of greater diameter than the bore of said sleeves and provided with a restricted central aperture, and conducting elements extending through said sleeves and insulated therewithin, the ends of said conducting elements extending through the bores of said washers and being bent back thereupon.

10 2. A device of the type described comprising, a body portion formed of insulating material and provided in opposed edges with spaced threaded bores arranged in pairs, and transverse bores formed in the side face thereof corresponding in number and arrangement to the pairs of bores and extending intermediate the inner ends thereof, threaded bores formed in said body portion connecting each bore of each of said pairs with its corresponding transverse bore, externally threaded electrodes adjust-

able within said last named bores, sleeves formed of insulating material and having one end thereof provided with external threads to engage the threads of said first named bores, washers disposed within said bores of greater diameter than the bore of said sleeves and provided with a restricted central aperture, conducting elements extending through said sleeves and insulated therewithin, the ends of said conducting elements extending through the bores of said washers and being bent back thereupon, said transverse bores being provided with a counterbore forming a shoulder, a sheet of transparent insulating material disposed against each of said shoulders and retaining rings holding said sheets in position.

In testimony whereof I hereunto affix my signature.

WILLIAM G. BENNETT.
